UNITED STATES PATENT OFFICE.

STANLEY MACOMBER, OF MASSILLON, OHIO, ASSIGNOR TO THE MACOMBER STEEL COMPANY, OF CANTON, OHIO, A CORPORATION OF OHIO.

STRUCTURAL UNIT.

Application filed February 16, 1923. Serial No. 619,401.

The present invention relates more particularly to the construction of a truss section or other structural unit for buildings and the like. The improved unit is a unitary member formed from a single piece of metal. While the particular object of the invention is the provision of a light weight section adapted to act as a beam in carrying light loads, as in the case of joists in floor construction, the utility of the invention is not limited to any such particular field or for that matter to any such particular type of structural element. My improved unit, in other words, may be also advantageously employed in the construction of columns, as a roof purlin and as a reinforcement for concrete in floors and the like.

To the accomplishment of the foregoing and related ends, the invention then consists of the means hereinafter fully described and particularly pointed out in the claims, the annexed drawings and the following description setting forth in detail one product exemplifying my invention such product constituting, however, but one of various applications of the principle of my invention.

In said annexed drawings:—

Fig. 1 is a plan view of the initial or starting plate from which my improved structural unit is fashioned by a succession of steps constituting a novel method of manufacture not claimed in this application, such plate being shown as slit or punched preliminarily to the performance of succeeding operations; Fig. 2 is a side elevation illustrating the form assumed by such plate as the result of such subsequent operations where it is desired to fashion the plate into a truss member; Fig. 3 is a vertical transverse section of such truss member, the plane of the section being indicated by the line 3—3, Fig. 2; Fig. 4 is a horizontal section of the same, taken on the plane indicated by the line 4—4, Fig. 2; Fig. 5 is a broken perspective view of such member; Figs. 6, 7, 8, 9, 10 and 11 illustrate various sections of the initial or starting plate which may be used in fashioning such element or structural unit; Fig. 12 is a diagrammatic representation in side elevation of such truss element showing its use as a beam or girder hung below supports; Fig. 13 is a view similar to Fig. 12 but showing

such element inverted above supports; Fig. 14 similarly shows the same employed as a roof purlin; Fig. 15 illustrates the use thereof as a beam or girder between columns, one of the latter consisting of such element 60 in modified form; Figs. 16 and 17 are sections likewise more or less diagrammatic in character illustrating the employment of such element in steel truss joist floor construction; and Fig. 18 shows such element 65 used as a support and reinforcement for concrete floor construction.

The initial or starting plate A, shown in plan in Fig. 1, is of elongated rectangular form and of flat cross section, the same as 70 shown in Fig. 6. The overall dimensions of the plate as well as its thickness will, of course, vary with the length which it is desired the finished structural unit shall have and the calculated strains and stresses 75 which such unit will be required to sustain. As already indicated, the initial step in the fabrication of such unit from the plate consists in the shearing, slitting or punching of the same along oppositely disposed, 80 irregular L-shaped lines α adjacent the respective ends thereof and along two parallel series of similar Z-shaped lines α' intermediate of such ends. It will be noted that the longitudinally extending portions 85 of the slits α and adjacent slits α' overlap and that similarly such longitudinally extending portions of the slits α' overlap each other; also that the narrow portions 1 of the metal sheet lying between such longitudinally extending slit portions are 90 designed to be bent transversely of the median line of the slit as a whole at points α^2 .

As a result of the form and arrangement of slits α and α' , when such portions 1 of the sheet are bent downwardly at the points α^2 , the effect will be to displace from the central portion 2 of the sheet the continuous, i. e., uncut, lateral portions 3 and 4, such continuous lateral portions being at the same 100 time shifted longitudinally in opposite directions relatively to the main portion 2. The lateral portions are then brought together, it being noted that the transverse portions of the zigzag or Z-shaped slits α' , 105 when the portions of the sheet are thus displaced, present shoulders 5 that are adapted to interlock, as shown in Fig. 4, substantially in the transverse plane of said central member 2. It will also be noted that the adja- 110

cent portions 1 of the strip extend in opposite diagonal directions, when viewed in side elevation, from the central strip portion 2 and the lateral strip portions 3 and 4 when these are thus brought into juxtaposition and interlocked in the fashion just described (see Figs. 2 and 5). Finally, it will be noted that, as shown in Fig. 3, such portions 1 incline inwardly or converge at their lower ends, such lower ends being substantially in longitudinal alignment while their upper ends are alternately attached to opposite sides of the mid-portion 2 of the sheet.

It will be obvious from the description thus given of the manner in which a sheet of metal is first cut or slotted and the resultant parts thereupon bent and fitted together, that a truss-like structure is formed, the mid-portion or rib 2 of the sheet constituting one chord, the juxtaposed and interlocked lateral portions 3 and 4 constituting the other chord and the diagonal portions 1 constituting the web members of the truss. The ends of such resultant truss member may be variously formed or arranged. Thus, as illustrated in Figs. 2 and 5 (see also Figs. 12 and 13), the relatively wide terminal portions 6 constituting the ends of the mid-rib portion 2 and the relatively wide terminal portions 7 constituting one end of the lateral chord-member 3 and one end of the lateral chord-member 4, which relatively wide terminal portions 6 and 7 remain attached to the mid-rib portion 2 and the lateral portions 3 and 4, are brought into overlapping relation in approximately the plane of such mid-rib portion and there riveted, welded or otherwise permanently secured together in any desired manner. As a result, not only is a true truss structure presented, but the terminal portions 6 and 7 thus secured together provide a convenient projection at each end of the truss for use as a bearing plate for such truss, whether the latter is hung below supports 10, as illustrated in Fig. 12, or is inverted above such supports, as shown in Fig. 13. It is also possible by bending these terminal portions 6 and 7, so that they will lie at an obtuse angle to the plane of mid-portion 2, or, in other words, to the median line of the truss, to adapt the latter for use in an inclined position between supports 11 and 12, as shown in Fig. 14, where use of the truss member as a roof purlin is illustrated. For that matter such terminal portions 6 and 7 may be bent at a right angle to the median line of the truss and the latter thus adapted to be secured against the vertical faces of columns 13 and 14, as shown in Fig. 15. In this last mentioned figure, the column 14 at the right illustrates still another adaptation of my truss, viz., as a column or vertical support, the only change involved being the overlapping of such terminal portions 6 and

7 so as to form a box-like end for the structure instead of a projection, as in the several forms hereinbefore described.

The specific form of my improved structural element shown in Figs. 2, 5 and 12 will find a large field of use as a joist in floor construction, examples of such use being illustrated in Figs. 16 and 17, where a series of such elements 15 are shown in diagrammatic cross-section. In Fig. 16 a concrete floor 16 with concrete finish 17 is shown as being supported by such joist, while a plaster ceiling 18 is hung therefrom in the usual manner. The only difference in the construction shown in Fig. 17 is that the concrete portion 16 of the floor has incorporated therein nailing strips 19 to which a wood floor finish 20 is attached.

The use of the element as a column illustrated in Fig. 15 renders unnecessary the separate illustration of the use of such element as a partition stud, except to note that where employed in this last mentioned manner, successive elements will be disposed so as to face in opposite directions, thus additionally bracing and strengthening the wall.

Such element 15, as illustrated in Fig. 18, is very well adapted for use in reinforcing concrete, the particular use illustrated in the figure in question being in a reinforced concrete floor or roof structure 20 of generally familiar form where the elements are wholly embedded in the concrete. The use of such elements in this connection presents the advantage that wood forms may be eliminated since permanent or removable steel forms 21, as shown at the right of said Fig. 18, may be supported on hangers attached to the elements 15. The latter, in other words, will support the dead load of the floor construction until the concrete has set and the same hangers 22 may be conveniently utilized to suspend the ceiling 23, if desired.

It is not considered necessary to show or describe any special machine or instrumentality, in the way of dies or the like, such as may be used in the commercial fabrication of my improved structural unit inasmuch as it is a matter of indifference how the slits be formed in the initial sheet A and the several portions of the latter thereupon brought into the relationship illustrated in Figs. 2 and 5. Obviously such unit can be fabricated by hand with ordinary tools where made from a sheet of light section. Moreover, while all the operations involved may be performed in the cold, I do not mean to exclude the possible use of hot bending where due to the thickness of the original sheet or for other reason this should be found advantageous. It is emphasized, however, that the unit is formed wholly by slitting and bending the original sheet or plate, there being no expanding or stretching of the metal whatever.

It has already been indicated that the thickness and the dimensions of the sheet employed in the fabrication of the unit will be selected with a view to providing the necessary strength for the particular use to which the unit is to be put. Instead of being of plain, i. e., flat cross-section, as shown in Fig. 6, such plate may be of irregular cross-section in order to provide additional thickness of material in certain of the parts of the unit when finished. Thus, as shown in Fig. 7, the central portion of the sheet A', from which the mid-rib or chord element 2 is cut, may be thicker than the respective lateral portions. A similar modification is illustrated in Fig. 8, except that such thickened central portion is narrower and somewhat higher; while in the plate or strip A³, shown in Fig. 9, such central portion is transversely curved or humped. In Fig. 10, the modified strip or plate A⁴ there shown is rolled with the central portion as well as the lateral portions thickened, the additional material being of curved cross-section, so that the mid-rib and lateral portions of the fabricated unit will take on the form of rods. Finally, in Fig. 11, I show a form of strip or plate similar to that shown in Fig. 7, except that the central portion is thickened on both sides.

It has already been explained that the terminal portions 6 and 7 when brought into overlapping relation may be secured together in any desired manner. Similarly, the lateral portions 3 and 4 of the unit when brought into juxtaposed relation may be welded, riveted or tied together at longitudinally spaced points, if desired.

It, of course, will be understood that while I have illustrated and described a number of practical applications or uses for my improved structural unit, it is not meant to restrict its use to any particular purpose.

Other forms may be employed embodying the features of my invention instead of the one here explained, change being made in the form or construction, provided the elements stated by any of the following claims or the equivalent of such stated elements be employed.

I therefore particularly point out and distinctly claim as my invention:

1. In a truss-like structural unit, the combination of three parallel spaced chord-members, the two outer members being spaced from the central member in a direction transverse of the plane thereof and laterally displaced toward each other to lie in a laterally juxtaposed relation substantially in the transverse plane of said central member, and a series of web-members integrally formed and connected at opposite ends with said chord-members, respectively.

2. In a truss-like structural unit, the com-

bination of three parallel spaced chord-members, the two outer members being spaced from the central member in a direction transverse of the plane thereof and lying in laterally juxtaposed and interlocked relation.

3. In a truss-like structural unit, the combination of three parallel spaced chord-members, the two outer members being spaced from the central member in a direction transverse of the plane thereof and lying in laterally juxtaposed and interlocked relation, and a series of web-members integrally formed and connected at opposite ends with said chord-members, respectively.

4. In a truss-like structural unit, the combination of three parallel spaced chord-members, the two outer members being spaced from the central member in a direction transverse of the plane thereof and lying in laterally juxtaposed and interlocked relation, and a series of web-members integrally formed and connected at opposite ends with said chord-members, respectively, said web-members being inclined to the plane of said chord-members.

5. In a truss-like structural unit, the combination of three parallel spaced chord-members, the two outer members being spaced from the central member in a direction transverse of the plane thereof and lying in laterally juxtaposed and interlocked relation, and a series of web-members, integrally formed and connected at opposite ends with said chord-members, respectively, said web-members being inclined in two different directions to the plane of said chord-members.

6. In a truss-like structural unit, the combination of three parallel spaced chord-members, the two outer members being spaced from the central member in a direction transverse of the plane thereof and lying in laterally juxtaposed and interlocked relation, the ends of said chord-members being fixedly secured together.

7. In a truss-like structural unit, the combination of three parallel spaced chord-members, the two outer members being spaced from the central member in a direction transverse of the plane thereof and lying in laterally juxtaposed and interlocked relation, and a series of web-members, integrally formed and connected at opposite ends with said chord-members, respectively, the ends of said chord-members being fixedly secured together.

8. In a truss-like structural unit, the combination of three parallel spaced chord-members, the two outer members being spaced from the central member in a direction transverse of the plane thereof and lying in laterally juxtaposed and interlocked relation, and a series of web-members, integrally formed and connected at opposite ends

with said chord-members, respectively, and said web-members being inclined to the plane of said chord-members, the ends of said chord-members being fixedly secured together.

9. In a truss-like structural unit, the combination of three parallel spaced chord-members, the two outer members being spaced from the central member in a direction transverse of the plane thereof and lying in laterally juxtaposed and interlocked relation, and a series of web-members, integrally formed and connected at opposite ends with said chord-members, respectively, said web-members being inclined in two different directions to the plane of said chord-members, and the ends of said chord-members being fixedly secured together.

10. In a truss-like structural unit formed from a single piece of metal, the combination of three parallel chord-members, of which a central member is spaced from two outer members in a direction transverse of the plane thereof, and a series of web-members connected at opposite ends to the central member and to said outer members, respectively, the ends of the metal piece each being formed into a central member end portion and one outer member end portion, the adjacent end portions of the central member and outer members being brought into overlapping relation to form unit-end bearing portions.

11. In a truss-like structural unit formed

from a single piece of metal, the combination of three parallel chord-members, of which a central member is spaced from two outer members in a direction transverse of the plane thereof, and a series of web-members connected at opposite ends to the central member and to said outer members, respectively, a comparatively wide end portion being formed on each end of said central member and a comparatively wide end portion on one end of one outer member and a comparatively wide end portion on the opposite end of the other outer member, the adjacent end portions of said central and outer members being brought into overlapping relation to form unit-end bearing portions.

12. In a truss-like structural unit formed from a single piece of metal, the combination of three parallel chord-members, of which a central member is spaced from two outer members in a direction transverse of the plane thereof, and a series of web-members connected at opposite ends to said chord-members, respectively, the ends of the metal piece each being formed into a central member end portion and one outer member end portion, said two outer members being laterally displaced toward each other to lie in a laterally juxtaposed relation, and the adjacent end portions of said central and outer members being brought into overlapping relation to form unit-end bearing portions.

Signed by me this 15th day of Feb., 1923.
STANLEY MACOMBER.
